UNITED STATES PATENT OFFICE.

MICHAEL A. ROLLMAN, OF MOUNT JOY, PENNSYLVANIA.

SHIPPING PACKAGE.

Application filed November 25, 1922. Serial No. 603,201.

To all whom it may concern:

Be it known that I, MICHAEL A. ROLLMAN, a citizen of the United States of America, and a resident of Mount Joy, 5 county of Lancaster, and State of Pennsylvania, have invented certain new and useful Improvements in Shipping Packages, of which the following is a full and clear specification.

10 The object of this invention is to so pack a plurality of disassembled ice-cream freezers that the cubical area of the package will be reduced to a minimum, to thereby save in freight charges.

15 In the drawing—

Fig. 1 is a vertical sectional view of the package;

Fig. 2 is a plan view thereof, with the top-flaps thrown open;

20 Fig. 3 is a view similar to Fig. 2, except that the parts in the upper part of the package are removed;

Fig. 4 is a group perspective of the disassembled parts of the freezer.

25 I have shown my invention as adapted to the type of freezer disclosed in my pending application Serial No. 499,494, filed September 9, 1921, which consists of a metal ice-bucket 5, a cream-can 6, a 30 cream-can top 7, a gearing-bridge 8, and a dasher 9. The bucket and cream-can taper downwardly their full length and are entirely without outwardly-projecting beads at their lower ends. The ice-bucket is provided with an external bead 10 near its 35 upper end.

I have illustrated my invention as applied to packing six complete freezers. The six ice-buckets are made into two nested sets and the sets are placed alongside each other in the shipping-box 11, one set being inverted to permit the tapered walls to come close together in overlapping relation. In view of the fact that there are 45 no external beads on the lower parts of the buckets, they fit snugly together the full extent of the telescoping, thereby preventing rattling in shipping. In view of this nice fitting of the nested buckets, it is important 50 to provide means for preventing them being jammed or wedged so tightly together as to be difficult to separate; for this purpose, I provide the aforesaid external bead 10, this bead being so positioned that it will 55 rest upon the top edge of the outer bucket

after the buckets have come to a nice fit, and thus prevent wedging.

The cream-cans are nested in the same manner and one set is placed in each of the bucket sets. In the space between the 60 cream-cans and the ice-buckets, the lids 7 and the dashers 9 may be packed, it being desirable to pack all the lids in one space and all the dashers in the other, the dashers being desirably enclosed in a paper 65 wrapper 12, to prevent them banging about and thus injuring themselves or the softer metal of the cream-cans.

After the foregoing parts have been packed in the manner set forth, I place on 70 top of the buckets a paper-board partition 13, and in the narrow space between this partition and the top wall of the container, I pack the gearing-bridges 8. These are packed alongside each other in overlapped 75 relation, so as to lie within the narrow space, the gearing-hangers 14 lying close together and serving to space the bridge-plates in such manner that the top ones will lie flat against the top wall of the 80 container and the underneath ones will lie flat against the upper surface of the partition-board 13. The handle-crank 75 are turned so as to lie in overlapped relation with the hand-grips against the end walls of 85 the box.

It will be observed that it is important that both the buckets and the cream-cans shall be tapered and also that the sizes of the buckets and cream-cans shall be so 90 proportioned that any given number of buckets when nested will provide a space approximately equal to the length of the nested set of an equal number of cream-cans.

95 What I claim is:

1. A shipping package for dismantled ice-cream-freezers of the type wherein the bucket and cream can are both tapered to provide nesting in shipping, the sizes of 100 the buckets and cream-cans being so proportioned that a given number of buckets when nested will provide a space in the inner bucket approximately equal to the length of the nested set of an equal number 105 of cream-cans, comprising a shipping box, two sets of such ice-buckets enclosed within said box side-by-side, each set consisting of a plurality of dismantled nested buckets, and two sets of such cream-cans each consisting 110

of a plurality of dismantled nested cream-cans, one set being enclosed within the outer bucket of each set of said ice-buckets.

2. In an ice-cream-freezer shipping package, a container, two sets of nested ice-buckets therein, a nested set of cream-cans placed within each set of buckets, can-tops and dashers placed within the spaces between the cream-cans and the buckets, 10 a partition placed on top of the nested buckets, and gearing-bridges lying in the space between the partition and the top wall of the container and abutting against said top wall and said partition, said 15 bridges lying in overlapped relation with their hand-cranks in overlapped relation and

the grips of these hand-cranks abutting the end walls of the container.

3. In an ice-cream freezer shipping package, a container, two sets of nested ice-buckets therein, a nested set of cream-cans placed within each set of buckets, can-tops and dashers placed within the spaces between the cream-cans and the buckets, a partition placed on top of the nested buckets, and 20 gearing-bridges lying in the space between the partition and the top wall of the container and abutting against said top wall and said partition.

In testimony whereof I hereunto affix my 25 signature.

MICHAEL A. ROLLMAN.
